(57) **CLAIM**

The ornamental design for an electronic tablet housing with card reader, as shown and described.

DESCRIPTION

FIG. 1 is an isometric view of an electronic tablet housing with card reader showing my new design;
FIG. 2 is a front elevational view thereof;
FIG. 3 is a top plan view thereof;
FIG. 4 is a bottom plan view thereof;
FIG. 5 is a left elevational view thereof;
FIG. 6 is a right side elevational view thereof; and,
FIG. 7 is a rear elevational view thereof showing my design.
